FLEXIBLE SHAFT WINDING TOOL

Clarence F. Hotchkiss, Jr., Binghamton, N. Y., assignor to Stow Manufacturing Company, Inc., Binghamton, N. Y., a corporation of New York

Original application January 18, 1943, Serial No. 472,770. Divided and this application October 7, 1943, Serial No. 505,349

5 Claims. (Cl. 57-11)

This invention relates to an apparatus and method of manufacturing flexible shafting of the type wherein a central core or wire is wound with one or more successive layers or convolutions of a plurality of wires with the successive layers or wire coats layered up on the core usually composed of a plurality of proper gauge wires and successive layers are usually wound in opposite directions.

An object of the invention is the construction of an apparatus whereby exceedingly long lengths of flexible shafting may be wound up in a semi-automatic manner. That is, the present machine is capable of forming lengths of shafting several hundred feet long and instead of requiring a long building similar to a rope walk the apparatus is considerably compacted whereby a length of shafting twice as long as the building may be wound.

A further object of the present apparatus is the formation of flexible shafting starting with a central core and winding a layer of wire thereon, together with the placing of successive layers over the first wound layer. In operation, the core or previously wound shaft is fed from a reel joined intermediately of two normally equal lengths of shafting in such a manner that only the intermediate section passes through the winding apparatus. That is, as the core or initially wound shafting is fed from a storage reel it is in three or more lengths joined by swivel connections so that the portion of the shafting being wound may be rotated on its longitudinal axis whereby succeeding layers are applied to the rotating section.

A still further object of the present apparatus is the novel construction of a winding tool and adjacently positioned winding head whereby the central core or initially wound cable is rotated on its axis to smoothly and tightly apply a layer or coat of wire thereto and simultaneously advance the wound shafting therethrough.

This general construction is disclosed and claimed in my copending application Serial No. 472,770, filed January 18, 1943, entitled "Apparatus and method for making flexible shafting." The present application is a division thereof and is directed to flexible shafting forming machine and a winding tool therefor whereby a plurality of continuous wire helices are applied to the exterior of a longitudinally moving and rotated flexible shafting core being moved through the machine.

In the drawings:

Fig. 1 is a diagrammatic layout of the entire

semi-automatic flexible shaft winding machine for carrying out the features of this invention;

Fig. 2 is a side elevation partly in cross-section of the winding or wire layering tool per se, illustrating the manner in which the successive layers of individual wires are wound upon the shafting core or initially wound shafting;

Fig. 3 is a vertical section taken on line 3-3 of Fig. 2 in the direction of the arrows; and

Fig. 4 is a similar vertical section taken on line 4-4 of Fig. 2.

It is believed that a general statement and explanation of the apparatus shown in Figure 1 will be of assistance in understanding the advantages and operation of the apparatus as a whole before describing the machine and its associated parts in detail.

Referring to Figure 1, the apparatus comprises generally a rotatable storage reel 1 carrying a core or previously wound shafting 3 and connected thereto by a swivel 5 is a further length of the core or initially wound shafting 7. This section 7 extends over pulleys 9 and 11 with intermediate supporting rollers 13 and, thence, around pulleys 15 and 17. The periphery of the roller 17 is at such a height that the core or wire passing thereover and to be wound is fed directly through a winding tool generally denoted by the numeral 19. A plurality of wires 21 carried on a supply stand 23 are fed into the winding tool 19 where they are wound upon the initial shafting 7 as it is drawn through the tool. Axial rotation is given to this entire section of core 7 and wound section 175 through the medium of a winding head 25. The head 25 imparts rotary movement to the sections 7 and 175 of the shafting and simultaneously pulls or feeds the wound shafting therethrough, the linear movement of the unwound and wound portions of the shafting being indicated by the direction arrows. The previously wound length 27 attached to the wound portion 175 of section 7 passes over pulleys or drums 29, 31 and 33 to a storage reel 35 positively driven by motor 37 and it will be obvious that the swivel 39 between these sections prevents the axial rotative movement between the section of the shafting being wound and the previously wound portion 27 thereof passing to the storage reel.

In the prior art, flexible shafts have usually been wound by stringing up a core and manually carrying along the core a perforated die plate through which wires are fed to lay on the successive convolute layers. Attempts have been made to eliminate these manual operations and to

create automatic or semi-automatic machines for carrying out these steps but until the advent of the present invention these prior attempts had not solved the practical difficulties involved particularly those encountered in forming larger diameter flexible shafting. As before stated, this apparatus permits a length of central core wire or a shaft which has been initially wound to be drawn and twisted during its passage through the machine, whereby a continuous, smooth, tight helix is wound upon the core or initial shaft in such a manner that a shaft of several hundred feet in length can be operated upon before readjusting the machine to carry out a further winding step.

The initial core or previously wound shaft 7 is separated from the remaining material on the reel 1 by a swivel 5, so that the entire length of the core or initial shafting 7 to be operated on turns on its longitudinal axis without imparting rotation to the portion 3. Swivel 39 prevents rotation between wound portion 27 and wound portion 175 of section 7.

The winding head 25 and winding tool or die 19 are mounted intermediate the lower pulleys 15 and 17 on a fixed base and are contiguous to each other. The winding head 25 through which the section 7 and wound portion 175 is drawn and rotated is positively driven by a jack shaft 101 suitably connected by belts or other power-transmitting means to a motor 100. The jack shaft is supported in antifriction bearings 102 mounted in the supporting frame 113. The winding head accomplishes two purposes, namely, the rotation of the shafting whereby the wires 21 feeding through winding tool 19 are layered up or wound upon the core or initially wound shaft and, secondly, the drawing through or imparting linear movement to the shafting as the winding progresses.

The draw plate or wire laying tool construction forming the present invention consists of an exteriorly threaded adjustable bushing 180 mounted in a holder 181 and maintained in any fixed desired position by set screw 182. A hardened end thimble 183 is inserted in the end of the bushing where the incoming wire strands contact the end of the bushing as they are laid on the shafting 7. The holder 181 is provided with an enlarged base portion 184, having a pair of spaced parallel and horizontal bores 185 therethrough, and is carried on a pair of parallel rods 186 secured in end plates 187 and 188. Coil springs 189 and 190 are carried on the rods 186 between the end of the base portion 184 and the end plate 188 and also between the opposite end of the base plate and stop collars 191. This permits adjustment of the position of the winding tool and the coil springs 189 and 190, and this arrangement will take up any shock or jar to which the shafting being wound may be subjected. The end of the base portion 184 opposite the outer end of the bushing 180 carries an upwardly extending partition 195 having a screw threaded opening therein for the retention of a wire guiding and draw plate 192. This plate has a central opening 193 in axial alinement with the bore of the bushing 180 and a plurality of wire receiving openings 194 radially and circumferentially arranged about the central opening. Wires 21 from the supply spools 23 mounted on a swivelable carrier are fed through the openings 194 and to the bushing 183 where they are guided and wound

upon the moving shafting 7. It will be observed that the opening 193 of the plate 192 and the bore of bushing 180 are in axial alinement and register with the opening in hollow driven shaft 131 of the winding head 25. The layer being wound up on the initial shafting 7 is indicated by numeral 175.

This novel method of forming large diameter flexible shafting and apparatus for carrying out the method allows exceptionally long lengths of shafting to be manufactured in a semi-automatic manner and within a comparatively small space.

What I claim is:

1. In a flexible shafting forming machine, in combination therewith of a winding tool for applying a plurality of continuous wire helices to the exterior of a longitudinally moving and rotating flexible shafting core being carried through said machine, said winding tool comprising a horizontal tube mounted in a holder through which said core is drawn, a vertical plate positioned in spaced relation to said tube, said plate having a central aperture therein alined with the said tube and a series of radially spaced wire passages circumferentially arranged about said central aperture and means for adjusting the relative position of the adjacent end of said tube with respect to said vertical plate and wherein the said tube holder and said vertical plate are integrally joined to a connecting base portion with the said connecting base portion being mounted on spaced apart parallel rods with the ends of the rods secured at their ends to longitudinally spaced brackets.
2. A flexible shafting machine and winding tool as claimed in claim 1 wherein the said base has longitudinal bores therethrough for the reception of the ends of said rods which are affixed in sockets, and springs surrounding said rods between the said base and the rod end sockets whereby the base is resiliently cushioned in both longitudinal directions.
3. A flexible shafting machine and winding tool as defined in claim 1 wherein the said central aperture and circumferentially and radially spaced wire passages are formed in a disc which is removable from an opening formed in the said vertical plate.
4. A winding tool for applying a wire helix to a linear moving and revolving member comprising a U shaped member mounted on a support with the spaced legs of the U shaped member upstanding, a horizontal tube carried in an opening through one of said legs and a draw plate carried in the other of said legs, said plate having a central opening therein aligned with the said tube and a series of wire directing openings therein circumferentially arranged in spaced relation to the said central aperture and wherein the said horizontal tube is externally threaded for adjustable positioning in the opening through one of the legs of the U shaped member and the draw plate is threaded into an opening passing through the other of said legs.
5. A winding tool as defined in claim 4 wherein the U shaped member is provided with a pair of horizontal and parallel arranged openings extending through the base thereof, and rods passing through said openings whereby said U shaped member may be adjustably positioned on said rods.

CLARENCE F. HOTCHKISS, JR.
